SIMPLIFIED DUPLICATING DEVICE

Irving Stockman, New York, N. Y., assignor of
one-half to Maurice Schoenbrun, New York,
N. Y.

Application June 2, 1945, Serial No. 597,365

13 Claims. (Cl. 101—126)

1

This invention relates to new and useful improvements in a simplified duplicating device.

More specifically, the present invention proposes the construction of a duplicating device characterized by having a base and a frame pivotally and movably mounted thereon, the frame having two pivotally connected members between which a stencil sheet is adapted to be stretched.

Still further, it is proposed to provide a device as aforesaid in which the frame can be quickly assembled and disassembled with and from the base.

Another object is to provide a device as aforesaid in which the frame is enlargable both in length and width.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a device constructed in accordance with this invention.

Fig. 2 is a section on the line 22 of Fig. 1, adjusted positions of the frame being indicated in dot-dash lines.

Fig. 3 is an enlarged section on the line 3—3 of Fig. 1, parts being shown in full.

Fig. 4 is an enlarged perspective view of the frame of the device of the present invention, a portion of the base also being shown.

Fig. 5 is a section on the line 5—5 of Fig. 4.

Fig. 6 is a section on the line 6—6 of Fig. 4.

Fig. 7 is an enlarged section of a portion of the frame.

Fig. 8 is a plan view of a device constructed in accordance with a modification of this invention.

Fig. 9 is a perspective view of a slide pad used with the device.

Fig. 10 is a perspective view of a device constructed in accordance with a further modification of this invention.

Fig. 11 is a perspective detailed view of the slide hinge used in this device.

The simplified duplicating device, according to this invention, comprises a base 10, which may be a rectangular block of wood. It has four legs 11 at its four corners. The top two legs 11 are bored axially providing sockets 12. A rod 13 having legs 14 is mounted in these sockets. The legs extend in these sockets and are pressed upwardly by springs 12a, located in the bottom of these sockets. Rod 13 thus traverses the top margin

2

of the base. Two movable guide strips 15 extend along the sides of the top face of the base, and may be secured at various positions by screws 15a which may slide in parallel slots 15b, formed in the base 10. The connection portion of rod 13 is rectangular in cross section. Two tubes 16, with rectangular openings are slidably mounted on rod 13. The outer periphery of these tubes is circular and is adapted to engage within a sleeve 16a from each of which extends a leg 17, and projects over the top face of the base.

A frame 18 is disposed on the top face of the base and connected to the legs 17, as will presently appear. The frame has a bottom frame member 19 the top face of which is covered by felt 20. A top frame member 21 is pivotally connected to member 19 by hinges 22 disposed at the upper end of the frame members 19 and 21.

Frame member 21 has two raised tubes 23 along 20 the top of its longitudinal sides, through each of which extends one of the legs 17. That is to say, to assemble the frame with the rod 13, the tubes 23 are merely slid over the legs 17. The frame is then pivotally mounted on the base to 25 swing about the tubes 16 on the rod 13 and normally held in upwardly inclined position by spring 13a. It may also be raised and lowered parallel to the base by movement of the legs 14 in the sockets 12.

Frame member 21 has a side tab 24 and top and bottom tabs 25 for facilitating the use of the frame. It is fastened at its bottom edge to the frame member 19 by snap tab 26. Scales 27 are marked along the inner sides and bottom of the frame member 21, or if desired may be indicated along the outer margin as well. Frame members 19 and 21 may be made of any desirable material. Frame member 21, due to its more complex construction, is best moulded in plastic.

Frame member 21 has, fixed to its under side, depending pins 28. Frame member 21 is adapted to be disposed on top of a sheet of stencil paper 29, and then with the stencil paper affixed thereto by means of pins 28, it is placed on top of the felt to be squeezed between the two frame members 19 and 21. Pins 28 pierce the stencil paper and extend into the felt, holding the stencil paper tightly in place.

The operation of the device is as follows:

Frame member 21 is placed on a sheet of stencil paper and is then secured between the frame members 19 and 21, as aforesaid, and the frame 50 18 is slid on the legs 17 of the rod 13. The frame can be moved transversely of the base by movement of the tube 16 along the rod 13, and can be

moved longitudinally of the base by sliding of the legs 17 in the tubes 23. Thus the frame can be disposed over any desired part of the base.

A stack of paper, on which pictures or printing are to be duplicated is placed in position beneath frame 18. All that is necessary to effect this duplication is to press the frame downwardly against the tension of spring 13^a, and simultaneously to slide an inking pad, such as the pad 30 shown in Fig. 9, over the top of the stencil paper. This pad will cause ink to flow through the perforations of the stencil sheet and thus will reproduce the design of the stencil sheet on the top paper of the layer of papers beneath the frame 18. The pad will stretch the stencil sheet slightly, the stencil sheet being firmly held by the pins 28. As soon as the top paper has been printed, the spring 13^a will swing the frame 18 upwardly on the rod 13 and the top sheet withdrawn. The frame is shown in a swung position in Fig. 2 by the inclined dot-dash figure, and in a raised position on a stack of papers by the horizontal dot-dash figure. As the papers of the stack are successively printed and withdrawn, the frame may be lowered closer to the base by pressing the legs 14 downwardly in the sockets 12. The snap fastener 26 holds the frame members together so that the frame 18 can be swung as a unit to withdraw each sheet of paper as it is printed.

A device constructed in accordance with a modification of this invention is shown in Fig. 8. It distinguishes from the previous device in that the tube 16' is made in two parts 16^a and 16^b telescoped together so that it can be expanded and contracted in length, and in that the frame 18' is made expandable and contractable lengthwise and crosswise so that its length and/or width can be changed. In order to make the frame changeable in size, both the frame members are made telescopic. Only frame member 21' is shown in Fig. 8 but it will be understood that frame member 19' is made similarly. Frame member 21' has its side members formed of two telescoped parts 21^a and 21^b and its top and bottom members formed of two telescoped parts 21^c and 21^d, each of the parts 21^c and 21^d being integral with its adjacent side member part. Thus the frame 18' can be quickly enlarged or made small to accommodate a larger or smaller sheet of stencil paper. Other parts of this device corresponding to similar parts of the device of Fig. 1 are indicated by like references with an accent added.

A device constructed in accordance with a further modification of the invention is shown in Fig. 10. It distinguishes from the device of Fig. 1 in that it cannot be moved over the base but must stay in one position. The rod 13'' has two right angle trunnions 31, and the frame member 21'' has two orificed lugs 32 in which the trunnions 31 are disposed, hinging the frame 18'' to the rod 13''. The trunnions 31 extend in the same direction so that frame 18'' can be quickly slid thereon or slid thereoff as desired.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A duplicating device comprising a base having sockets at its upper corners, a U-shaped rod having vertical legs in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet.

2. A duplicating device comprising a base having sockets at its upper corners, a U-shaped rod having vertical legs in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet, and a snap on said top frame member adapted to secure said frame members together for swinging as a unit above said bar.

3. A duplicating device comprising a base having sockets at its upper corners, a U-shaped rod having vertical legs slidably disposed in said sockets and a bar connecting said legs and traversing the upper margin of said base, a slide hinge slidably and rotatably mounted on said bar and having spaced straight legs extending over said base, said spaced straight legs being held in a normally inclined position by a coil spring engaged on said bar, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby a stack of paper disposed between said base and said frame may have the print of said stencil successively reproduced thereon by successively sliding an inking pad on top of said stencil sheet and removing the papers of said stack one by one as said print is reproduced thereon, said vertical legs being pressed into said sockets after a number of sheets of paper have been removed.

4. A duplicating device comprising a base having sockets at its upper corners and adjustable guides along its side edges for guiding a stack of

papers disposed on said base, a U-shaped rod having vertical legs slidably disposed in said sockets and being held in raised position by springs in the said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby the sheets of paper of said stack may have the print of said stencil reproduced one by one thereon by successively sliding an inking pad on top of said stencil sheet, and removing the top sheet of paper after each sliding.

5. A duplicating device comprising a base having sockets at its upper corners and adjustable guides along its side edges for guiding a stack of papers disposed on said base, a U-shaped rod having vertical legs slidably disposed in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby the sheets of paper of said stack may have the print of said stencil reproduced one by one thereon by successively sliding an inking pad on top of said stencil sheet and removing the top sheet of paper after each stamping, said top frame member having scales around a plurality of sides of its inner and outer margin for coaction with said stencil sheet.

6. A duplicating device comprising a base having sockets at its upper corners, a U-shaped rod having vertical legs in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said bottom frame member having a felt lining on its top surface, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet.

7. A duplicating device comprising a base having sockets at its upper corners, a U-shaped rod having vertical legs in said sockets and a bar con-

necting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs said bottom frame member having a felt lining on its top surface, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet, said top frame member having depending sharp points adapted to pierce said stencil sheet and felt for holding said stencil sheet tightly stretched between said frames during said sliding.

8. A duplicating device comprising a base having sockets at its upper corners, a U-shaped rod having vertical legs in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby a sheet of paper disposed between said base and said frame may have the print of said stencil reproduced thereon by stamping an inking pad on top of said stencil sheet, said first mentioned tube having two telescoped parts and said frame being expandable transversely and longitudinally for accommodating different size stencils.

9. A duplicating device comprising a base having sockets at its upper corners, a U-shaped rod having vertical legs in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet, said first mentioned tube having two telescoped parts and said frame being expandable transversely and longitudinally for accommodating different size stencils, each of said frame members having telescoped parts effecting said expansion.

10. A duplicating device comprising a base having sockets at its upper corners, a U-shaped rod

having vertical legs in said sockets and a bar connecting said legs and traversing the upper margin of said base, and a frame hinged to said bar and having two superposed hinged frame members, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet.

11. A duplicating device comprising a base having sockets at its upper corners, a U-shaped rod having vertical legs in said sockets and a bar connecting said legs and traversing the upper margin of said base, and a frame hinged to said bar and having two superposed hinged frame members, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet, said hinge between said frame and bar including two right angle trunnions rigid with said bar and two lugs on said frame mounted on said trunnions.

12. A duplicating device comprising a base having sockets at its upper corners, a U-shaped rod having vertical legs in said sockets and a bar connecting said legs and traversing the upper margin of said base, and a frame hinged to said bar and having two superposed hinged frame members, said frame members being adapted to hold between them a sheet of stencil paper hav-

ing an imprint to be duplicated whereby a sheet of paper disposed between said base and said frame may have the print of said stencil reproduced thereon by sliding an inking pad on top of said stencil sheet, said hinge between said frame and bar including two right angle trunnions rigid with said bar and two lugs on said frame mounted on said trunnions, said trunnions facing in the same direction whereby said lugs can be slid thereon and thereoff.

13. A duplicating device comprising a base having sockets at its upper corners, a U-shaped rod having vertical legs in said sockets and a bar connecting said legs and traversing the upper margin of said base, a slide hinge slidably and rotatably mounted on said bar and having spaced straight legs extending over said base, and a frame disposed on said base having two superposed hinged frame members, the top member having spaced tubes along its sides slidably mounted on said tube legs whereby said frame can be moved crosswise of said base by movement of said tube on said bar and lengthwise of said base by movement of said top frame member on said tube legs, said frame members being adapted to hold between them a sheet of stencil paper having an imprint to be duplicated whereby a sheet of paper disposed between said base and said frame may have the print of said stencil reproduced thereon by sliding an inking pad on top of said stencil sheet, a pair of movable guides adjustably mounted on said base by bolts engaging parallel grooves formed in the said base.

IRVING STOCKMAN.
